UNITED STATES PATENT OFFICE.

ANTON J. HAUG, OF NASHUA, NEW HAMPSHIRE, ASSIGNOR TO THE IMPROVED PAPER MACHINERY COMPANY, OF NASHUA, NEW HAMPSHIRE.

CENTRIFUGAL PULP-SCREEN.

1,106,808.

Specification of Letters Patent. Patented Aug. 11, 1914.

Application filed June 29, 1910, Serial No. 569,458. Renewed November 22, 1913. Serial No. 802,365.

To all whom it may concern:

Be it known that I, ANTON J. HAUG, a subject of the Emperor of Germany, and a resident of Nashua, in the county of Hillsboro, State of New Hampshire, United States of America, have invented certain new and useful Improvements in Centrifugal Pulp-Screens, of which the following is a specification.

10 The object of this invention is to produce a centrifugal screen having features of novelty and advantage, of simple construction and having a high efficiency at a low operating cost.

15 I have illustrated my invention as embodied in a machine for screening pulp and will describe this embodiment of the invention.

Figure 1 is a side view in central vertical section of a machine embodying my invention. Fig. 2 is an end view in central vertical section. Fig. 3 is a detailed perspective view of part of a screen drum.

20 Referring to the drawings *a* denotes the machine casing, which comprises a horizontally arranged cylindrical shell *a'* and end plates *a²* *a²'*. *b* is a shaft supported in bearings *b'* *b*' at each end of the casing and extending through said casing. *s* denotes 25 the screen drum, which is cylindrical in form and is supported at each end from the inner walls of the end plates. The screen illustrated in the drawings and described herein is of the stationary type, though it 30 is not essential to the operation of the device that it should be.

35 Arranged centrally of the length of the casing is an inlet *i* which passes through the shell and screen drum and then branches 40 toward each end of the machine in feed spouts 10—10, which are of course located within the screen drum and spaced therefrom. These spouts have holes near their outer ends through which the stock is delivered to the interior of the screen drum.

45 Mounted on the shaft within and near each end of the casing are hubs 15—15, carrying disks 16—16, from the outer edges of which project blades 17—17, which extend 50 between the screen drum to the feed spouts

10—10. The shaft is intended to rotate at a high rate of speed, and these blades catch the pulp as it is delivered through the openings at the ends of the feed spouts, and throw it against the screen drum with such force as to cause the fine pulp to pass through the screen against the inner wall of the casing, whence it drops to the bottom of the machine and passes out through the pulp outlet *o*. The blades are oppositely inclined toward the center of the machine, as illustrated, in order to give the pulp a tendency to move toward the center of the machine, with the result that the slivers and coarser particles which cannot 60 pass through the screen travel from each end of the machine toward the center where they are delivered to the sliver outlet *o'*. To make sure of clearing the interior of the machine from slivers which collect at 65 the center, I prefer either to project a circumferential ring 20 just inside of the screening drum as illustrated in Fig. 3 which will cause the slivers when they strike this ring on either side to drop and pass out 70 of the sliver outlet, or I can cut away the center of the screen and interpose a trough 75 22 which will receive the slivers and carry them down to the sliver outlet at the lower part of the machine, as illustrated at *O'* in 80 Fig. 1.

It will be seen that as the stock is fed only through the outer ends of the feed spouts it will be thrown against the outer ends of the screen drum, and then moved toward the 85 center of the machine. The screening operation is a continuous one, and there will always be a steady current of slivers toward the center of the machine.

The screening operation is practically an 90 instantaneous one, that is to say the screening is all done at the moment when the pulp is thrown against the screen by the blades. Such pulp as is not screened at this operation is carried along with the slivers and 95 lost in the waste. In order to bring the machine up to the highest point of efficiency, and to prevent such waste of stock, I introduce a shower pipe 30 inside of the blades, preferably near the lower part of the ma- 100

chine, this pipe being pierced at intervals along the side to project the water toward the screen.

The water is picked up by the blades and thrown against the inner surface of the screen in the form of a spray, which beats upon the stock which is moving toward the center of the machine, washing through the screen any good stock which is being carried along with the slivers. With the use of a comparatively small amount of water the efficiency of the screening operation can be very materially increased without materially increasing the amount of water in the stock.

15 The machine made in accordance with my invention is simple in its construction, has a large capacity, is extremely efficient in its screening operation and easily handled and controlled. The inclination of the blades 20 may be varied for stock of different densities, that is to say if a heavy stock with a small amount of water in it is to be screened, the inclination of the blades can be reduced, giving such stock as is not screened at the 25 first impact a longer time to travel across the face of the screen, during which it is subjected to the action of the spray from the shower pipe, while with a thinner stock which will screen more readily, the inclination 30 of the blades may be increased. Also, if desired, the feed spouts can be shortened up to deliver the stock near the center of the machine, and the blades can be inclined in directions opposite to those illustrated in the 35 drawings, forcing the slivers toward the ends of the machine, where they can be collected and removed through two separate outlets. This is merely a variation of which a machine made in accordance with my invention is susceptible.

I claim as my invention:

1. In a machine of the character described, the combination with a casing and a cylindrical screen drum located therein, of an inlet 45 extending through said casing and said screen drum intermediate the length thereof, said inlet having lateral extensions within the screen drum and spaced therefrom, outlets near the ends of said lateral extensions, 50 separate outlets from the casing for the slivers and the screened pulp, and means located between said lateral extensions and the screen drum for delivering the stock to the screen drum for causing the slivers to move 55 toward the sliver outlet.

2. In a machine of the character described a horizontal cylindrical casing, a shaft extending therethrough, a cylindrical screen drum located within said casing, a set of 60 paddles supported from said shaft at each end of the machine and extending toward the center thereof, said paddles being adapted to rotate with their outer edges in close proximity to said screen drum, the paddles

of one set being inclined oppositely to those 65 of the other set and inclined rearwardly with respect to their direction of rotation toward the center of the machine, an inlet arranged intermediate the length of the machine and extending into the interior of the 70 screen drum, and feed spouts extending from each side of said inlet within the plane of said paddles and having delivery openings near the opposite respective ends of the screen, a shower pipe located within said 75 screen drum and arranged inside of said paddles; a sliver outlet in communication with the screen drum at its central part and a pulp outlet in communication with the interior of the casing.

80 3. In a machine of the character described a horizontal cylindrical casing, a shaft extending therethrough, a casing drum located within said casing and supported at its end from the end walls of said casing, collecting 85 means arranged circumferentially of said screen drum near its center, a sliver outlet in communication with the interior of said screen in the plane of said collecting means, an inlet arranged intermediate the length of 90 the machine and extending into the interior of said screen drum, feed spouts extending from each side of said inlet toward the ends of the machine and spaced from said screen drum; paddle blades located in 95 and adapted to rotate through the annular spaces formed between the screen drum and said feed spouts, said blades being supported from their outer ends by said shaft, the blades at one end being inclined oppositely 100 to those at the other end, said inclination being toward the center of the machine and rearwardly with respect to the direction of rotation of said blades, a shower pipe located within said screen drum and inside of 105 said blades and extending lengthwise said screen drum, and a pulp outlet in communication with the interior of said casing.

110 4. In a machine of the character described the combination with a casing and a cylindrical screen drum located therein, of an inlet extending through said casing and said screen drum intermediate the length thereof, said inlet having lateral extensions within the screen drum and spaced therefrom, outlets near the ends of said lateral extensions, 115 a pulp outlet from the casing, a sliver outlet communicating with the interior of the screen intermediate the ends thereof, and means located between said lateral extensions and said screen drum for delivering stock to said screen and for causing slivers to move toward the center of said screen to the sliver outlet.

120 5. In a machine of the character described, 125 the combination with a casing of a cylindrical screen drum located therein of a stock inlet extending through said casing and said

screen drum intermediate the length thereof, said inlet having lateral extensions within the screen drum and spaced therefrom, outlets near the ends of said lateral extensions, 5 separate outlets from the casing for the slivers and the screened pulp, and a plurality of paddle blades located in and adapted to rotate through the space between the said lateral extensions and the screen drum, 10 said blades being inclined rearwardly with respect to the direction of rotation from the said stock outlets toward the sliver outlet.

6. In a machine of the character described a horizontal cylindrical casing, a shaft extending therethrough, a cylindrical screen drum located with said casing, a set of paddles supported from said shaft at each end of the machine and extending toward the center thereof, said paddles being adapted 15 to rotate with their outer edges in close proximity to said screen drum, the paddles of one set being inclined oppositely to those of the other set and inclined rearwardly with respect to their direction of rotation toward 20 the center of the machine, an inlet arranged intermediate the length of the machine and extending into the interior of the screen drum, and feed spouts extending from each side of said inlet within the plane of said 25 paddles and having delivery openings near the opposite respective ends of the screen, a sliver outlet in communication with the screen drum at its central part and a pulp outlet in communication with the interior of 30 the casing.

7. In a machine of the character described a horizontal cylindrical casing, a shaft extending therethrough, a screen drum located within said casing and supported at its end 40 from the end walls of said casing, collecting means arranged circumferentially of said screen drum near its center, a sliver outlet in communication with the interior of said screen in the plane of said collecting 45 means, an inlet arranged intermediate the length of the machine and extending into the interior of said screen drum, feed spouts extending from each side of said inlet toward the ends of the machine and spaced 50 from said screen drum, paddle blades located in and adapted to rotate through the annular spaces formed between the screen drum and said feed spouts, said blades being supported from their outer ends by said 55 shaft, the blades at one end being inclined oppositely to those at the other end, said inclination being toward the center of the machine and rearwardly with respect to the direction of rotation of said blades, and a 60 pulp outlet in communication with the interior of said casing.

8. In a machine of the character described, a horizontal cylindrical casing, a shaft extending therethrough, a screen drum located

within said casing and supported at its end 65 from the end walls of said casing, collecting means arranged circumferentially of said screen drum near its center, a sliver outlet in communication with the interior of said screen and with said collecting means, stock 70 feeding means extending into the interior of said screen and having discharge openings near opposite ends of the screen, paddle blades located in and adapted to rotate through a space formed between the screen 75 drum and the stock feeding means, said blades being supported by said shaft, the blades at one end being inclined oppositely to those at the other end, said inclination being toward the center of the machine and rearwardly with respect to the direction of rotation of said blades, and a pulp outlet in communication with the interior of said casing.

9. In a machine of the character described, 85 the combination with a casing of a cylindrical screen drum located therein, a stock inlet having a lateral extension with a discharge orifice near one end of the screen drum and adapted to deliver the stock thereat, a pulp 90 outlet in communication with the interior of the casing, a sliver outlet communicating with the interior of the screen and located approximately in alinement with said stock inlet, and means interposed between said 95 drum and said lateral extention for delivering the stock against said drum and causing the slivers to travel lengthwise the drum toward the sliver outlet, said means comprising a series of rotatable paddle blades inclined rearwardly with respect to the direction of rotation from the stock delivery outlet to the sliver outlet.

10. In a machine of the character described a horizontal casing, a shaft extending therethrough, a screen drum located within said casing, a sliver outlet in communication with the interior of the screen and intermediate the ends thereof, stock delivering means extending into the interior 105 of said screen and having discharge openings for discharging stock at the respective opposite ends of the screen, paddle blades located in and adapted to rotate through spaces between the screen and said discharge 110 openings, said blades being supported by said shaft and the blades at one end being inclined oppositely to those at the other end, said inclination being toward the center of the machine and rearwardly with the direction of rotation, and a pulp outlet in communication with the interior of the casing.

11. In a machine of the character described, the combination with a casing of a cylindrical screen drum located therein, a stock inlet extending through the casing and the screen drum intermediate the length thereof, said inlet having discharge openings

within the screen drum, sliver discharge means communicating with the interior of the drum, a pulp outlet communicating with the interior of the casing, and a series of 5 paddle blades within the drum and between the stock inlet means and the casing, said blades being inclined rearwardly with re-

spect to the direction of rotation from the stock delivery discharge openings to the sliver discharge means.

ANTON J. HAUG.
